I. GLADSTONE

BRASSIÈRE

Filed Nov. 3, 1923

Inventor

Ida Gladstone
By her Attorney
Harry Radzinsky

UNITED STATES PATENT OFFICE.

IDA GLADSTONE, OF NEW YORK, N. Y.

BRASSIÈRE.

Application filed November 3, 1923. Serial No. 672,461.

To all whom it may concern:

Be it known that I, IDA GLADSTONE, a citizen of the United States, and a resident of the city, county, and State of New York, ⁵ have invented a new and useful Improvement in Brassières, of which the following is a specification.

This invention relates to a brassière such as is worn by women for the support of the bust, and has for its object to provide an article of this character which will support the bust firmly under all conditions of use; which will be of simple construction; which will prevent irritation and chafing from ¹⁰ perspiration, especially in warm weather, and which will, by reason of its construction, be of especial use to stout persons.

A further object of this invention is to provide an article of this character which ²⁰ will keep the breasts of the wearer separated and will tend to avoid irritation and chafing sometimes caused when brassières of the conventional form are worn.

With these objects, and such other objects ²⁵ as may hereinafter appear, in view, I have devised the particular arrangement of parts set forth below, and more particularly pointed out in the claim appended hereto.

Reference is to be had to the accompanying drawing, forming a part hereof, in which—

Figure 1 is a perspective view, showing my improved brassière as it appears when in use;

Figure 2 is a view of the inner face of the brassière;

Figure 3 is a sectional view on the line 3—3 of Figure 2, looking in the direction of the arrows; and

Figure 4 is a sectional view on the line 4—4 of Figure 2, looking in the direction of the arrows.

Throughout the various views of the drawings, similar reference characters designate similar parts.

In the preferred embodiment of my invention, as disclosed in the accompanying drawing, 1 indicates the body of the garment, which is in the conventional form and ⁵⁰ which is suitably shaped to fit the body of the wearer. The body portion 1 is provided with the usual shoulder straps for the support of the garment, and also with conventional closure means at its edges consisting of the hooks 3 which are intended

to detachably engage with the eyes on the opposite edge of the body. The eyes just referred to are indicated at 4 in Figure 2.

The inner face of the body portion 1 is provided with suitable bust pockets 5 which ⁶⁰ are located on opposite sides of the center line of the garment, and which are of sufficient fullness and capacity to receive and support the breasts of the wearer and hold the same separated. The pockets 5 are secured to the body of the garment by the stitching 6.

Located on the center line of the garment, and at a point intermediate of the pockets 5, is an elastic strip 7, which is secured for ⁷⁰ a portion of its length, to the body of the garment by the stitching 8. The lower, or free end of the strip terminates in a loop 10 which holds a fastening plate 11 which is intended for attachment to any article ⁷⁵ of wearing apparel worn by the wearer, so that the brassière will be held down snugly on the wearer and the strip 7 will be held under tension.

The upper end of the body 1, of the garment, is formed in a plurality of gatherings or shirrings, as at 9 at the upper end of the strip 7 and intermediate of the pockets 5. The stitches 8 form these shirrings, and when tension is placed upon the strip 10, it tends to draw down the shirred portion 9 and causes the upper part of the brassière to snugly follow the curvature of the body and suitably confines the breasts of the wearer with resilient pressure. ⁸⁰ ⁸⁵

The pressure exerted by the elastic member or strip 7 at the upper central portion of the garment and between the bust pockets 5 tends to retain the breasts of the wearer in separated position under all conditions ⁹⁵ of wear and prevents irritation of the same caused by chafing.

The gathering or shirring of the garment at the point disclosed also provides fullness at the breast portions such as is ¹⁰⁰ required to enable the garment to fit the wearer properly.

From the foregoing, it is obvious that my invention is not to be restricted to the exact embodiment shown, but is broad enough to ¹⁰⁵ cover all structures coming within the scope of the annexed claim.

Having described my invention, what I claim is:—

An article of the class described com- ¹¹⁰

prising a brassière having a pair of spaced bust pockets on its inner face, an elastic dividing strip extending transversely of the brassière and intermediate of said bust pockets, said strip being fixedly secured to the inner face of the brassière, with the brassière gathered or shirred adjacent its upper end and at a point intermediate of

said pockets and the free end of said strip having means for attachment to the apparel of the wearer to hold said strip under tension and cause the garment to snugly conform to the wearer. 10

Signed at the city, county and State of New York, this 30th day of October, 1923.

IDA GLADSTONE.
